UNITED STATES PATENT OFFICE.

MILON J. TRUMBLE, OF LOS ANGELES, CALIFORNIA, ASSIGNOR, BY MESNE ASSIGNMENTS, TO SIMPLEX REFINING COMPANY, A CORPORATION OF CALIFORNIA.

PROCESS FOR REFINING PETROLEUMS.

1,259,171.

Specification of Letters Patent. Patented Mar. 12, 1918.

Application filed September 27, 1909. Serial No. 519,883.

To all whom it may concern:

Be it known that I, MILON J. TRUMBLE, a citizen of the United States, residing at Los Angeles, in the county of Los Angeles and 5 State of California, have invented a new and useful Process for Refining Petroleum, of which the following is a specification.

My invention consists in subjecting a hydrocarbon oil to the emulsifying action 10 of heated water to effect a breaking up of the molecular structure of such oil and to also effect a separation of the more volatile portion thereof.

My invention furthermore consists in repeatedly subjecting a hydrocarbon oil to the 15 emulsifying action of heated water at constantly increasing temperatures to effect a comparative effectual breaking up of the molecular structure of such oil and separating 20 the more volatile portions of such oil at each repeated subjection of the oil to the action of the heated water.

My invention also consists in subjecting 25 natural gases evolved from oil wells or gases of like nature to the action of vapors of hydrocarbon oil and water and subsequently condensing the same.

Another object of the invention is to provide for the production and refining of clear 30 illuminating oils from distillation without necessitating the use of chemicals such as sulfuric acid or caustic soda.

A further object of the invention is to provide for the recovery of the lightest and 35 most volatile hydrocarbons which pass over in the beginning of distillation.

Another object of the invention is to provide for production of commercial oils from 40 natural gases which are evolved from oil wells and which are ordinarily wasted.

The process has been particularly applied in connection with oils having an asphaltum base, such as California petroleum, and especially in connection with the final refining 45 and separation of the final products from the oils which are known as distillates, being the lighter products of the first distillation of crude oil.

The apparatus hereinafter described for 50 carrying out the process forms the subject matter of my application of even date herewith. Serial No. 519,884 now Patent 1,002, 474. Sept. 5, 1911.

The said apparatus as shown is adapted 55 for effecting the separation of one product

of a predetermined gravity from an oil to be treated. Other apparatus or units of the same structure are employed in the further separation of the oils which have not been vaporized and which pass from the first apparatus with the outflowing water. Several different units may be used in the several required steps taken to effect the different fractionations which may be desired. In the present instance I have only shown an apparatus sufficient to effect the separation of one product.

The accompanying drawings illustrate an apparatus suitable for carrying out the process.

Figure 1 is a plan of the apparatus.

Fig. 2 is a side elevation, partly in section, of that portion of the apparatus in which the oil and oil vapor are subjected to the action of steam and hot water for fractional separation and refinement thereof.

Fig. 3 is a perspective of said separating apparatus with parts broken away.

Fig. 4 is a transverse section thereof on line x^4-x^4 in Fig. 5.

Fig. 5 is a horizontal section on the line x^5-x^5 in Fig. 4.

1 designates a fire-still which may be of any usual or suitable construction and is provided with a vapor outlet pipe 3. 4 85 designates the burner or heating means for the still which may be an oil burner. The outlet pipe 3 from the still is inclosed in a jacket 5 for receiving cooling medium, as hereinafter set forth, for condensing the 90 vapor.

The separating apparatus proper consists of a casing 6 with two horizontal partitions or plates 7, 8 dividing the interior of the casing into three superposed chambers. Vertical partitions 10 extend from the bottom of the casing 6 to the lowermost horizontal plate 7, dividing the space therebetween into a plurality of compartments 11 extending side by side. The pipe line 3 for condensing the oil vapor opens into the first compartment 11 near the top thereof and an opening 12 is provided in the wall 10 between said chamber and the next compartment 11 near the top thereof for the overflow of liquid 100 from the first compartment 11 to the next chamber. A similar opening 12' is provided in the next vertical wall 10 for the passage of liquid from the second to the third compartment and a similar opening 12'' in the 110

next wall 10 for the passage of liquid from the third to the last compartment, it being understood that any desired number of chambers may be used, each compartment 5 communicating with the preceding and the succeeding compartment. A hood 13, acting as a trap, is provided for each opening 12, etc., to prevent passage of steam from one compartment to the next. The openings 12, 10 12', etc., are provided alternately near opposite ends of the walls 10, so that the liquid in passing through the compartments is caused to traverse substantially the entire length of each compartment and the said 15 openings in successive walls 10 are at successively lower levels, so that the liquid is maintained at the highest level in the first compartment, at a lower level in the next compartment and so on. The final compartment 20 11 is connected near its bottom with the oil outlet pipe 14 leading to the tail house 15 where it may be connected, through valve 16, 17 with the tanks 18, 19, for the heavier qualities of oil, such as benzin or 25 kerosene. Valves 20, 21 are provided in the respective pipes 3 and 14 adjacent to the separating apparatus.

The plate 7 which forms the top of the compartments 11 is provided with a plurality of perforations or openings 22, the plate being formed with lips or raised walls 23 around said openings. The chamber 24 between this plate 7 and the upper division plate 8 forms a condensing chamber for the lighter products of the oil, an outlet pipe 25 being connected with this chamber and leading to the tail house 15 where it is connected to the gasolene or light gravity oil tank 27. A steam supply pipe 30 28 extends into each of the chambers 11 near the bottom thereof and is provided with a series of perforations preferably in the bottom of the pipe, said pipe extending substantially the entire length of the chamber, 35 so as to distribute steam throughout the body of oil in the chamber. Each pipe 28 is provided with a valve 29 and said pipes are connected to a common supply pipe 30 leading to a suitable source of steam, for example, boiler house 31. A drain pipe 32 may also be provided in the bottom of each chamber 11, said drain pipe being normally closed by a valve 33.

The oil delivery pipes 14 and 25 may extend parallel to one another and are inclosed by a water jacket 34. The upper chamber 35 of the casing 6, above the division plate 8, is provided with a connection for the supply of cooling water thereto, a perforated 40 pipe 36 extending in said chamber for admission of water and a delivery pipe 37 leading from said chamber for the discharge of the water. Means are provided for circulating a current of water through the water 45 jacket 34, said water being supplied from

a tank 38 by a pump 39 through a pipe 40 to the water jacket 34 near the tail end thereof. The farther or head end of the water jacket 34 is connected to the water supply pipe 36 for the water chamber 35 and the outlet pipe 37 from said chamber is connected with the adjacent end of the water jacket 5, the farther end of said water jacket being connected by pipe 40' to the water tank 38 into which it discharges. 75

A by-pass pipe 42 connects the two pipes 3 and 14 and is provided with a valve 43, by opening of which the vapor from the still is allowed to pass through the pipe 14 to the tail house without passing through the separator. 44 designates an independent supply connection to the pipe 3 adapted for the admission or supply of natural gas or other gas which may be used in the process when it is desired to condense gas and 45 designates a supply pipe for distillate or other hydrocarbon which is injected into the pipe 5 by steam supplied by pipe 46 provided with a valve 47. An independent oil supply connection 48, for example, from a pump 90 line, leads into the first compartment 11, to supply oil thereto from an independent source, if desired.

The process is carried out as follows: Steam is generated in the boiler house 31 95 and water is circulated through the system of water jackets 34, 5 and the water chamber 35 of the separator with the result that the compartments 11 of the separator become filled with water up to the level of the respective outlets 12 thereof. In the form of the invention herein illustrated the necessary quantity of water to charge the compartments 11 may be supplied by the condensed steam. It will be understood, however, that the initial charge of water for these compartments, may be supplied by introducing hot water in any desirable manner, as for instance, through the steam pipes 28. Assuming that the process is being used 110 for the refining and separation of distillates, the stock or base distillates or hydrocarbons are pumped through the pipe 2 to the fire-still and said still is operated with fire heat alone, and without steam, so as to 115 maintain a steady heat on the oil or distillate therein causing the distillates to vaporize, the vapor passing off through the vapor line 3. The circulation of water through the jacket around said vapor line causes 120 condensation of the vapor, so that the product enters the first compartment 11 of the separator wholly or partly in a liquid condition. A constant supply of hydrocarbon oil suitable for treatment may be supplied by 125 any other suitable means capable of furnishing a constant or regular amount of oil. The steam entering through the pipe 28 into the said first compartment of the separator is more or less condensed by contact with the 130

oil or condensed oil vapor and at the same time heats said oil and there is thus produced in the first compartment a body of oil and water, and after the process is under 5 way and in normal operation, the said first compartment 11 is filled with water containing more or less oil up to the level of the overflow 12 and the liquid overflowing through said overflow collects in the next 10 compartment 11 and overflows through the overflow 12' thereof and so on in the succeeding compartments, each compartment being occupied by a body of water containing oil up to the level of the overflow 15 therein, said water resulting from condensation of the steam supplied through the pipe 28 leading into said compartment and said oil resulting from condensation of the oil vapor supplied through the pipe line 3. It 20 will be understood that the bodies of water in the several compartments are hot, the heat abstracted by the vaporization of a portion of the oil being sufficient to condense the steam into water, but not sufficient to 25 cool the water below the boiling point. The space above the overflow in each compartment is occupied by vapors of water and oil and is herein referred to as the "steam space." In said first compartment the heat 30 which is supplied to the body of hot water therein through the medium of the steam pipes keeps the water, and the oil which is supplied through the pipe 3, in a constant state of violent agitation, and the action of 35 the steam and hot water while so agitated, causes emulsification of the oil and imparts sufficient heat to the oil to cause part of the lighter constituents, for example, gasoline, to pass upwardly as vapor through the 40 openings 23 in the top of the compartment. Such portion of the condensed distillate as is not vaporized in this manner in the first compartment overflows while in an emulsified condition, together with a portion of 45 the hot water in which the condensed distillate is contained, into the next compartment, where on account of the greater amount of steam space in the upper portion of the compartment and the correspondingly smaller amount of liquid in the lower 50 portion of said compartment, a higher temperature is imparted to the liquid and an additional quantity of vapor is driven off, the liquid being in this manner subjected 55 to a series of heating operations at progressively higher temperatures and in contact with a body of water. In the apparatus disclosed the outlet openings 22 from the compartments 11 are of such relative size to the 60 combined areas of the steam inlet openings in each compartment as to create a certain amount of back pressure, whereby it is possible to raise the temperature above that of the boiling point, the amount of steam admitted to each compartment being con- 65

trollable by the valves 29. The primary effect of the progressively higher temperatures is as stated to drive off from the condensed distillate the lighter vapors therein contained. It is of advantage to operate 70 upon the oil in the manner stated by causing it to be subjected to the heat of the bodies of water of successively higher temperatures in which the oil is contained, even when the portions of vapor thereby distilled 75 by the heat imparted by such bodies of water are collected together in a single product, for the reason that the action of the hot water on the oil is exerted more efficiently when acting in this graduated 80 manner, and I have found that by treating the oil with bodies of water of successively higher temperatures a larger amount of the more valuable high gravity oil is obtained. The oil vapors which are expelled from the 85 compartments 11 and pass upwardly into the chamber 24 are subjected therein to the cooling influence of the body of water in the water chamber 35 and are thereby condensed, passing out through the gasoline 90 line 25 to the gasoline tank.

I have found that the above described operation and the action of the hot water and steam on the condensed oil vapor suspended and intermixed with the water and steam in 95 the form of an emulsion, causes such an alteration in the product that the lightest and most volatile vapors which are not generally subjected to condensation, are by this operation rendered capable of being ab- 100 sorbed by the gasoline and dissolved therein as they pass off through the gasoline line 25 along with the gasoline vapors which are condensed by the cooling effect of the water flowing in the water jacket 105 34. In fact, I have found that it is possible to absorb and dissolve portions of the natural gas such as escapes from the oil as it is pumped from oil wells by admitting it to the vapor inlet pipe 3 along with the 110 condensed vapor from the still or along with distillate admitted through the pipe 45 without operation of the still. In either case there is produced from the gas a condensable product which liquefies in the gaso- 115 line 34 and can be drawn off into the gasoline tank. That portion of the condensed vapor product from the inlet pipe 3 which is not subject to vaporization by the successive action in the compartments 11, 120 passes from the final compartment 11 through the pipe 14 to the benzine or kerosene tanks in the tail house, along with any excess water of condensation, said water settling out from the oil and being 125 drawn off as required by connections 50.

The process is also applicable for the separation and refining of oil without preliminary distillation, such oil being led directly from the pump line through the pipe 48 130

4
into the first compartment 11 and being subjected in its passage through the successive compartments to the action of hot water and steam at successively higher temperatures to cause the lighter products to pass upwardly into the condensing chamber 24, the lighter and heavier products passing from the separator by the pipe lines 25 and 14, as before described. The process is generally applicable to hydrocarbon oils of any kind, for example, distillates, and if applied to such oils without previous treatment, it will in general produce oils of sufficiently definite composition and purity for commercial use. I have, for example, treated by this process dark stock distillate having a gravity of about thirty eight producing kerosene with a gravity of about forty five and gasoline of a gravity of about sixty five, the kerosene and gasoline so produced being water white and free from objectionable odor. The odorous and coloring matter is absorbed by the water of condensation in the compartments 11 and passes off with said water. In this connection it is important that the water should be absolutely pure and this is insured by the use of water of condensation only.

While my process enables chemicals to be dispensed with, such chemicals may be used if desired, and in some cases, for example, in treating crude oil directly in one distillation, the usual chemical treatment with sulfuric acid and followed by washing with caustic soda solution may be employed, the first distillation in that case, being run through the separator to produce the final product. I prefer however to use the first distillation as stock for the distillation in this process as above stated.

In carrying out my process, it is necessary to maintain the temperature of the water and oils in the separate compartments not lower than the temperature at which water produces steam; and other means may be employed to maintain the requisite temperature in the body of oil and water, to thereby subject the oil to the presence of steam.

50 What I claim is:

1. The process of refining petroleum which consists in introducing the petroleum successively into bodies of water at successively higher temperatures, passing steam into said bodies of water to maintain the temperatures thereof and to thoroughly agitate the oil therewith, thereby producing an emulsion of oil and water and causing a portion of the oil to be vaporized in each body of water, subsequently condensing the portions so vaporized, and drawing off the unvaporized portions along with the water and separating the water therefrom.

2. The process of treating hydrocarbons which consists in introducing a hydrocarbon

gas together with hydrocarbon oil into a body of water, passing steam into said body of water to supply heat thereto and to thoroughly agitate the same, thereby producing an emulsion of the oil and water and causing the gaseous and vaporous products to be expelled from the body of water, and subsequently condensing said gaseous and vaporous products into liquid form.

3. The process of refining petroleum by the successive application thereto of heating media of increasing degrees of temperature, comprising introducing the petroleum into a heated body of water, thereby vaporizing a portion of such petroleum, withdrawing the unvaporized oil from the water and introducing it into another body of water having a higher temperature than the first named body of water, whereby the second named body of water further vaporizes the petroleum, withdrawing the vapors and condensing the same, and withdrawing the petroleum from the heated water.

4. The process of refining petroleum by the successive application thereto of heating media of increasing degrees of temperature, comprising introducing the petroleum into a body of hot water, heating such water to a temperature sufficient to thoroughly agitate the oil and water, thereby producing an emulsion and partially vaporizing a portion of the petroleum, withdrawing the unvaporized petroleum from the water and introducing it into another body of water, heating such second named body of water to a higher temperature than the first named body of water to further volatilize the petroleum, withdrawing the vapors evolved and condensing the same, and withdrawing the residue of petroleum from the last named body of water.

5. The process of refining petroleum which consists in introducing the petroleum successively into bodies of water at successively higher temperatures, introducing a heating medium into the first body of water in such manner as to thoroughly agitate and to emulsify the oil and water, and heating the successive bodies of water to successively higher temperatures in their respective progressive order while agitating the oil and water to emulsify the same, thereby producing a partial vaporization of the petroleum in each of the bodies of water, withdrawing the vapors and condensing the same, and withdrawing the residue of petroleum from the last body of water.

6. A continuous process of refining petroleum which comprises introducing the petroleum into a body of water and subjecting such water and petroleum to a temperature sufficient to emulsify and agitate the same and cause a portion of the petroleum to vaporize, withdrawing the unvaporized petroleum from the top of such body of water

and introducing the same into another body of water and subjecting such petroleum and water to a higher temperature than the first named temperature, whereby the emulsifying action of water at successively higher temperatures acts upon the petroleum to separate the volatile component parts thereof from the heavier parts thereof by degrees, withdrawing the vapors and con-

10
densing the same, and withdrawing the residue of petroleum from the water.

In testimony whereof, I have hereunto set my hand at Los Angeles, California, this 20th day of September, 1909.

MILON J. TRUMBLE.
